UNITED STATES PATENT OFFICE.

DONALD CAMPBELL, OF NEW YORK, N. Y.

TOY OR GAME.

975,119.

Specification of Letters Patent.

Patented Nov. 8, 1910.

Application filed June 16, 1910. Serial No. 567,129.

To all whom it may concern:

Be it known that I, DONALD CAMPBELL, a citizen of the United States, residing in the city of New York, borough of Manhattan, 5 in the county and State of New York, have invented certain new and useful Improvements in Toys or Games, of which the following is a specification.

My invention relates to toys or games, or 10 more particularly to a toy or game in which printed subjects may be mechanically manipulated to produce puzzling and amusing combinations.

I will first describe one form of embodiment of my invention, and will then point 15 out the novel features in the claims.

In the accompanying drawings,—Figure 1 is a face view of a toy or game embodying my invention; Fig. 2 is a cross-section 20 taken on the plane 2—2 of Fig. 1; and Fig. 3 is a view similar to Fig. 1, showing the movable members set into a different position.

My invention contemplates the employment 25 of two relatively movable members, at least one of which is to be a rotary disk, and in the preferable form there are two overlapping disks having different (fixed or movable) centers, in which case there will be 30 a frame or support on which the members are rotatively mounted. On the two relatively movable members or disks are applied printed subjects, such for example as those seen in the drawings, each of which is 35 split or divided so that a part of it appears on each disk, whereby each of such subjects is capable of having its two halves separated from each other.

In accordance with the above the drawings 40 show at A the first disk, and at B the second disk, the two being relatively movable. Although the centers of the disks might be otherwise arranged, they are shown in the present embodiment as separated from 45 each other, namely by a distance less than the sum of the radii of the two, so that one of the disks, for example B, overlaps the other at the edge portion. The disks having separate centers, there is shown a frame 50 C which may be termed a support, and to which the two disks A and B are pivoted. It thus appearing what the purpose of the support C is, it will be clear that the same might be modified indefinitely in form.

55 While as shown it consists only of a back piece, it might have both back and front

pieces, or merely a front piece, in which latter case the front piece would be apertured so as to disclose the printed surfaces of the disks.

60 Referring now to the two disks A and B, I prefer to have them centrally pivoted, although they could be varied in this respect, and I also prefer that at least one of them shall be circular in form. The disk A is 65 shown circular, but the disk B, while it might be the same shape, is shown as polygonal, it for convenience being provided with five sides, forming of it a pentagon.

70 The advantage of having the overlapping disk in the form of a polygon is that the division line indicated at $x-y$ of each subject is a straight line rather than an arc of a circle, which better enables the subject to be centrally divided and simplifies the 75 designing of the printed surfaces.

75 So far as the construction of the disks is concerned, it is obvious that their relative size can be altered without departing from the scope of the invention, and while disks 80 to the number of two are shown, the idea is to have a plurality thereof and a plurality of separated centers of rotation.

85 The printed subjects appearing upon the disks are preferably pictorial illustrations, such for example as pictures of animals, flowers, or the like. In the drawings the subjects are shown as consisting of pictures of common or barnyard animals, namely the cow, cat, goat, rabbit and dog, and comprised with each printed subject as a part of it is the name of the animal printed beneath it, the name being especially chosen as a compound name susceptible of being divided. By the arrangement described, each 90 of the subjects can be divided with respect not only to its picture but its name, and the corresponding halves of the picture and name of another animal may be substituted. In this way with disks having five subjects 95 on each, twenty-five combinations can be made, and for a child the toy can be used as a puzzle, the question being to find the proper halves corresponding to each other for each of the animals.

100 While I have shown portions of five subjects on each of the disks, it is obvious that the number can be changed indefinitely and in some cases more subjects might be placed on one disk than the other.

110 The method of pivoting the two disks to the support is immaterial, and for conven-

ience I have shown common eyelets D for that purpose, see Fig. 2.

It is clear that as shown the disks A and B are so constructed and fitted that each 5 may freely rotate independently of the other. One's rotation does not depend on the other's position. The cow's rear half and word "cow" may remain stationary with disk B, while disk A is rotated to cause the opposed 10 portions or front halves of the "puppy," "bunny," etc., to justify with the cow's rear half. Both the picture and the name (which latter is chosen of a double, that is compound or composite, character) are divided 15 on rotation, and each may justify with opposed portions of picture and name of analogous subjects; and as only one complete picture can be formed at a time, it results that the complete pictures are invariably 20 upright, which manifestly is an advantage as the support has then never to be altered in position.

Having described my invention, what I claim as new and desire to secure by Letters 25 Patent, is:

1. A toy or game comprising a pair of overlapping disks rotating about separated centers with a plurality of pictorial subjects applied thereto partly on each disk.
2. A toy or game comprising a pair of overlapping disks rotating about separated centers with a plurality of pictorial subjects applied thereto partly on each disk, the division of the several subjects being 35 such that each subject portion will justify with the opposed portion of any other subject.
3. A toy or game comprising a pair of overlapping disks rotating about separated centers with a plurality of pictorial subjects applied thereto partly on each disk, the upper disk being polygonal.
4. As an article of manufacture, a toy or game comprising in combination a support 45 to which disks are rotatively connected, a rotating disk connected to said support, a second rotating disk connected at a different point on said support so as to overlap the first disk at its edge, and a plurality of subjects printed or applied to said disks, each subject being partly on the first, partly on the second disk.
5. As an article of manufacture, a toy or game comprising in combination a support 55 to which disks are rotatively connected, a rotating disk connected to said support, a second rotating disk connected at a different point on said support so as to overlap the

first disk at its edge, and a plurality of subjects printed or applied to said disks, each 60 subject being partly on the first, partly on the second disk; said second disk being polygonal so that the subject division lines are straight.

6. As an article of manufacture, a toy or 65 game comprising in combination a support to which disks are rotatively connected, a rotating disk connected to said support, a second rotating disk connected at a different point on said support so as to overlap the 70 first disk at its edge, and a plurality of pictorial subjects printed or applied to said disks, each subject being partly on the first, partly on the second disk; said second disk being polygonal so that the subject division 75 lines are straight.

7. As an article of manufacture, a toy or game comprising in combination a support to which disks are rotatively connected, a rotating disk connected to said support, a second rotating disk connected at a different point on said support so as to overlap the first disk at its edge, and a plurality of subjects printed or applied to said disks, each 80 subject being partly on the first, partly on the second disk; and each subject consisting of the picture of an object, as an animal, in connection with the compound or double name thereof so arranged that picture and name are both divided and each portion 85 capable of being justified with opposed portions of other analogous subjects.

8. A toy or game comprising a pair of adjacent disks rotating about separated centers with a plurality of pictorial subjects applied thereto partly on each disk, said disks being 90 so constructed and fitted that each may freely rotate independently of the other.

9. A toy or game comprising a pair of adjacent disks rotating about separated centers with a plurality of pictorial subjects applied thereto partly on each disk, said disks being 95 so constructed and fitted that each may freely rotate independently of the other, 100 and said subjects being of such character and location that on rotating one or both disks, one portion of any of said subjects 105 may be justified with the opposed portion of any of said subjects.

In witness whereof I have hereunto set my hand, this 15th day of June, 1910.

DONALD CAMPBELL.
